UNITED STATES PATENT OFFICE.

WILLIAM A. McCORD, OF HASKELL, OKLAHOMA.

MUSIC-SHEET CABINET.

1,294,685.

Specification of Letters Patent.

Patented Feb. 18, 1919.

Application filed February 26, 1918. Serial No. 219,294.

To all whom it may concern:

Be it known that I, WILLIAM A. McCORD, a citizen of the United States, residing at Haskell, in the county of Muskogee and State of Oklahoma, have invented certain new and useful Improvements in Music-Sheet Cabinets, of which the following is a specification.

This invention relates to cabinets, and it 10 relates more particularly to an improved music sheet cabinet.

One of the objects of this invention is to provide for storing or filing music sheets in such systematic and convenient order that 15 the musician or user of the music may find the desired music sheet without unnecessary delay.

Another object of the invention is to provide a cabinet or music sheet file in which 20 the music sheets are thoroughly protected from dust and other detrimental influences.

Another object of the invention is to provide a filing cabinet in which the music sheets or folios are juxtaposed in vertical 25 position, so that any folio or sheet may be removed without interference by the other sheets.

Another object is to provide means for automatically bringing all of the music 30 sheets from their normal protected position into view and into easy reach of the user upon opening the cabinet or filing case.

Another object of the invention is to provide a flexible element connecting the lid 35 with an elevator or carriage which holds the music sheets, and simple and efficient tensioning means for said flexible element.

Another object is to provide a device of this character in which all of the working 40 parts are normally hidden from view, so that the cabinet or filing case presents a slight and ornamental appearance according to the exterior finish thereof.

Another object is to provide an improved 45 guiding device which is constructed for efficiently coöperating with the flexible element which raises and lowers the elevator or music sheet receptacle.

Another object is to provide an improved 50 form of tab or indexing element, one of which is to be applied to each sheet or folio of music contained in the music sheet receptacle.

Another object is to provide the lid of the cabinet with a chart which is referred 55 to by numerals or other reference characters on the tabs of the respective music sheets.

Another object of the invention is to provide a cabinet of this character which is so simple of construction that it may be manufactured at the minimum cost consistent 60 with its thorough efficiency and practicability.

Other objects and advantages may become apparent to persons who read the following 65 details of description in connection with the accompanying drawings, in which:—

Figure 1 is a vertical sectional view through my improved cabinet when in its open or operative position, the section being taken along the line 1—1 of Fig. 2:

Fig. 2 is a top plan view of the cabinet in its open position:

Fig. 3 is a horizontal sectional view along the line 3—3 of Fig. 1:

Fig. 4 is a vertical sectional view of the cabinet in its closed position, the section being taken along the line 4—4 of Fig. 5:

Fig. 5 is a vertical sectional view taken along the line 5—5 of Fig. 4:

Fig. 6 is a bottom plan view of the cabinet in its closed position, the weight and a portion of the hoisting cord or cable being removed:

Fig. 7 is a plan view of one of the tabs 85 to be attached to the music sheets, and

Fig. 8 is a perspective view of one of the tabs in its folded position, or in position to be attached to an edge of a music sheet.

Referring to these drawings in detail, in 90 which similar reference characters correspond to similar parts throughout the several views, the body 10 of the cabinet is preferably rectangular in horizontal section and in vertical section, and is primarily 95 open at its bottom and top and is provided with posts or blocks 11 which serve to reinforce and strengthen the body 10, to serve as leg elements, and also to serve as stops or seats upon which the elevator or music sheet 100 receptacle 12 normally rests. Moreover, the body is provided with oppositely disposed grooves or guide ways 13 in which a pair of longitudinally slotted bars, ribs, or guides 14 are slidably, the said guides 14 each being 105 secured in a groove 15. The grooves 15 are

formed in opposite sides of the elevator 12, and the ribs or guides 14 are secured therein by any appropriate means.

Each of the bars or ribs 14 is slotted 5 throughout its length as indicated at 16, (Fig. 1) thereby providing a passage in each of the guides 14 through which the flexible element or hoisting cable 17 may move during its operation. Moreover, each of the 10 guides 14 is provided with a bracket or bearing member 18 at its lower end; and each bearing member 18 carries a roller 19 around or under which the cable 17 extends. The lower ends of the guides 14 depend beyond 15 the lower end of the elevator 12, and a beam or strut 20 has its opposite ends secured respectively to the lower ends of the elements 14. Each of the bearing members or brackets 18 bridges or spans the joint between the 20 elements 14 and 20 and thereby provides means for securing these elements together, while, in turn, being supported by the elements 14 and 20.

The ends of the cable 17 are secured respectively to studs or other fastening means 21, while the intermediate portion of this cable supports a weight 22, and two portions of the cable between the weight 22 and the securing elements 21 engage with the wheels 30 or pulleys 19, while two other portions of the cable engage with wheels or pulleys 23. In order to accommodate the pulleys 23 without interference with the raising and lowering of the elevator, the body 10 is recessed so as to provide a cavity 24 at the upper end of each groove 13 and in communication therewith. Each cavity 24 is somewhat deeper at its middle portion than at its opposite sides, the latter being only sufficiently deep at the points 25 to receive one 35 of the brackets or pulley bearings 26. In each of the brackets 26 is mounted one of the wheels or pulleys 23, and the cable 17 engages with these pulleys and extends 40 through the openings 27 in the tops of the brackets 26. These brackets 26 are each formed of a blank of sheet metal and have one edge portion turned at right angles to the main portion of the bracket, as most 45 clearly shown in Fig. 5.

The securing elements 21 are carried by the lid 28, the latter being hinged to the body 10 at 29, and it will be seen, therefore, that when the cabinet is opened, the securing elements 21 draw the cable 17 upward and rearward until the lid 28 is in its fully opened position, as shown in Figs. 1 and 2. This movement of the cable 17 first takes up the slack in the latter, and then begins to raise 55 the elevator 12; and when the lid is fully opened, the elevator is held at its highest position by means of the cable 17, securing members 21, and pulleys 23.

The elevator 12 is preferably provided 60 with partitions 30 of which there may be

any desired or appropriate number, the purpose of these partitions being to separate the music sheets into groups or classes and, at the same time, hold the music sheets in their substantially vertical position independently 70 of the music sheets of the other groups. The partitions 30 are preferably recessed at 31 so that the central portion of the upper edge of each music sheet is exposed to view when the elevator is raised, the side walls of the 75 elevator which are parallel with the partitions 30 being also recessed to correspond with the recesses 31 of the partitions. By this means, the upper edges of the music sheets are adequately supported by the upper edges 80 of the side walls and partitions, while the tabs or indexing elements 33, shown in Figs. 7 and 8, are presented to the unobstructed vision of the user through the recesses 31. The tabs 33 are preferably provided with an adhesive coating 34, so that they may be quickly and easily applied to the music sheets.

The lid 28 is preferably provided with a plate 35 which provides a seat for an index sheet or chart 36. This chart is preferably of the form shown in Fig. 2, in which the names of the pieces of music may be entered respectively between the parallel lines, as indicated at 37, while the numbers of the sheets 95 which correspond with the names may be printed in columns as indicated at 38. These numbers correspond with the numbers on the tabs 33, and the tab numbers of each tab are preferably printed in reverse relation to one 100 another, as shown in Fig. 7, so that these numbers may be read with equal facility from either side of the music sheet.

In practice, I may provide a set of the tabs in a single sheet, so that the tabs may be cut 105 or otherwise severed from the sheet as they are needed, and I may so mark or perforate the outline of each tab that it may be torn from the sheet in the same manner that a postage stamp is torn from the sheet. 110

The plate 35 is apertured at 39 to allow movement of the cable ends about the securing member 21, which latter are positioned substantially in an invisible position, because of the relative darkness within apertures 39. Moreover, because of the position of the securing members 21 with relation to the hinges 29, the cable 17 helps to support the lid when in its open position, the weight of the elevator exerting a tension on the 115 cable so as to effect an upward pull on the lid.

From the foregoing, it will be seen that I have provided a device of this character which is of great utility and importance for 120 the purpose intended.

While I have described this embodiment of my invention in minute detail, it is to be understood that my invention is not limited to these exact details of construction and ar- 130

angement of parts shown and described in the foregoing, but my invention is susceptible of such changes that do not constitute a departure from the inventive idea disclosed in the appended claims.

What I claim as my invention is:

1. A hollow body, having opposed vertical guide-ways, an elevator movable vertically in the body, ribs at opposite sides of the elevator coacting with the said guide-ways and projecting below the elevator and having grooves in their outer faces, a strut connecting the lower ends of the ribs, guide pulleys at the lower ends of the ribs and at the upper ends of the said guide-ways, a cover hinged to the body, a flexible element extending beneath the strut, through the grooves of the ribs and through the said guide-ways, and over the lower and upper guide pulleys, and secured at its ends to opposite sides of the cover, and a weight on the lower portion of the flexible element below the said strut.
2. A hollow body, having opposed vertical guide-ways, an elevator movable vertically

in the body, ribs at opposite sides of the elevator coacting with the said guide-ways and projecting below the elevator and having grooves in their outer faces, a strut connecting the lower ends of the ribs, brackets secured to the ends of the strut and underlapping the lower ends of the ribs, guide pulleys at the outer ends of the brackets, other guide pulleys at the top of the body in line with the guide-ways thereof, a cover hinged to the body, a flexible element passing beneath the strut, around the pulleys of the brackets, thence up through grooves of the ribs and through the said guide ways and over the pulleys at the top of the body and having their ends attached to opposite sides of the cover, and a weight on the part of the flexible element beneath the said strut.

In testimony whereof I affix my signature in presence of two witnesses.

WILLIAM A. McCORD.
